UNITED STATES PATENT OFFICE.

FREDERICK F. BISCHOFF, OF CHICAGO, ILLINOIS.

HAND-WHEEL FOR VALVES.

SPECIFICATION forming part of Letters Patent No. 643,460, dated February 13, 1900.

Application filed August 24, 1899. Serial No. 728,385. (No model.)

To all whom it may concern:

Be it known that I, FREDERICK F. BISCHOFF, a citizen of the United States, residing at Chicago, in the county of Cook and State of Illinois, have invented certain new and useful Improvements in Hand-Wheels for Valves; and I do hereby declare the following to be a full, clear, and exact description of the invention, such as will enable others skilled in the art to 10 which it appertains to make and use the same.

My invention relates to a novel construction in a hand-wheel for valves and the like, the object being to provide a cheap, light, durable, and ornamental wheel which has a maximum radiating surface to keep it constantly cool; and it consists in the features of construction and combinations of parts herein- 15 after fully described and claimed.

In the accompanying drawings, illustrating 20 my invention, Figure 1 is a plan view of a hand-wheel constructed in accordance with my invention. Fig. 2 is a sectional view of the same on the line 2 2 of Fig. 1.

My invention consists of a hand-wheel 25 formed of sheet metal in two pieces A and B. Said part A consists of a circular plate having a square central depression C, and said part B likewise consists of a similar plate of larger diameter, also provided with a square 30 central depression D, in which and said de- pression C of part A a nut or square plate E, of heavy metal, is held. The outer edge of said part B is provided with a plurality of slots F, each extending at an angle to an 35 intersecting radial line, and is subsequently annularly dished adjacent said edge and likewise annularly flanged, said flanged edge being subsequently bent over to form an annular hollow G at the edge of said part B. Said part A is mounted upon said part B before 40 said flange is bent over, and the edge of said flange is forced down upon said plate A and soldered or otherwise secured thereto, thereby forming a complete hand-wheel, said 45 slots F serving as ventilating-openings for said annular hollow G, thereby preventing the latter from becoming hot, and likewise serve to give to said wheel a rough or practically milled surface, whereby it can be more firmly 50 gripped. Said slots F may also be formed by

sawing through the felly after the wheel is completed. Said parts A and B may be further secured together in any desired manner. A plurality of perforations are punched through the flat portion of the wheel and a 55 central opening tapped through said depressions C and D and said nut E to enable said wheel to be rigidly mounted on a valve-stem.

My device is extremely simple and cheap to manufacture, besides being very ornamental, affording good grip, and remaining 60 always cool.

I claim as my invention—

1. A hand-wheel for valves, comprising two plates each provided with a polygonal central 65 depression adapted to receive a heavy plate, and an encircling hollow felly provided with openings for permitting the free circulation of air therethrough, whereby the same is kept cool. 70

2. A hand-wheel for valves, comprising two plates each provided with a polygonal central depression adapted to receive a heavy plate, one of said plates being of greater diameter than the other and having its outer edge turned over to form a hollow felly in which the edge of said smaller plate is secured, and slots in said felly for ventilating the latter to keep same cool, and form a gripping-surface thereon. 75 80

3. A hand-wheel for valves, comprising two plates each provided with a polygonal central depression adapted to receive a heavy plate, one of said plates being of greater diameter than the other and having its outer edge turned over to form a hollow felly in which the edge of said smaller plate is secured, and slots in said felly for ventilating the latter to keep same cool, and form a gripping-surface thereon, and a central opening through 85 said central depressions in said plates and through the plate therein to enable said wheel to be rigidly mounted on a valve-stem, substantially as described. 90

In testimony whereof I affix my signature 95 in presence of two witnesses.

FREDERICK F. BISCHOFF.
